(57) **CLAIM**

The ornamental design for a data projector, as shown and described.

DESCRIPTION

FIG. 1 is a front, top and left side perspective view of a data projector, showing our new design;

FIG. 2 is a front view thereof;

FIG. 3 is a rear view thereof;

FIG. 4 is a top view thereof;

FIG. 5 is a bottom view thereof;

FIG. 6 is a left side view thereof; and,

FIG. 7 is a right side view thereof.

The broken lines are for illustrative purposes only and form no part of the claimed design.
